Primary Examiner — L. A. Grabenstetter

(57) **CLAIM**

The ornamental design for a loudspeaker enclosure, as shown and described.

DESCRIPTION

The patent or application file contains at least one drawing executed in color. Copies of this patent or patent application publication with color drawing(s) will be provided by the Office upon request and payment of the necessary fee.

1.-2. Loudspeaker enclosure

1.1 : Perspective

1.2 : Perspective

1.3 : Front

1.4 : Back

1.5 : Left

1.6 : Right

1.7 : Top

1.8 : Bottom

2.1 : Perspective

2.2 : Perspective

2.3 : Perspective

2.4 : Right

2.5 : Back

2.6 : Left

2.7 : Front

2.8 : Top

2.9 : Bottom

For design 1 the parallel fine lines shown in the drawings indicate the relief of the surface of the product, not surface decoration.

Regarding FIGS. 1.2 and 1.8, the portions of the article shown with yellow color translucent overlay form no part of the claimed design.
